CLAIM

The ornamental design for a graphical user interface for a computer display, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all copyright rights whatsoever.

The FIGURE is a front view of a graphical user interface for a computer display showing our new design.

The broken line drawings of the images within the graphical user interface are for illustrative purposes only and form no part of the claimed design.
